15 Claims. (Cl. 196—47)

This invention relates to furnaces provided with radiant heating means and contemplates the provision of heating apparatus constructed with a plurality of combustion or fire chambers in order to furnish a greatly increased area of most effective heat absorbing surfaces. The major object of the invention is to provide a heating apparatus having a large area of most effective heat absorbing surfaces.

An equally important object of the invention is to provide a heating apparatus in which several streams of oil may be heated simultaneously and the temperature of each stream controlled by the provision of separate heating chambers therefor.

Another object of the invention is to provide a heating apparatus constructed as a single furnace having an oil heating duty in excess of anything previous.

With these and other objects in view, which may be incident to the improvement, the invention consists in the parts and combinations to be hereinafter set forth and claimed, with the understanding that the several necessary elements comprising the invention may be varied in construction, proportions and arrangement without departing from the spirit and scope of the appended claims.

The invention broadly contemplates a unitary furnace structure provided with a plurality of fire chambers, each of which supplies radiant heat to elements arranged within the furnace, and with a common convection chamber into which the furnace gases from the several fire chambers are directed.

The invention is particularly adapted for the heating of hydrocarbon oils and in this connection contemplates the provision of a maximum amount of radiant heating surface adapted for applying heat to the oil.

In order to make the invention more clearly understood, there is shown in the accompanying drawings, means for carrying the same into practical effect without limiting the improvements in their useful applications to the particular construction which, for the purpose of explanation, have been made the subject of illustration.

In the drawings:

Figure 1 is a diagrammatic sectional elevation of a particular embodiment of the invention showing heating means as applied to two separate streams of oil.

Figure 2 represents a diagrammatic sectional elevation of modified apparatus also shown as adapted for heating two separate streams of oil.

Figures 3 and 4 are left and right-hand views, respectively, in diagrammatic sectional elevation of another modification shown as applied to the heating of a single stream of oil.

Figure 5 is a flow diagram in perspective illus-

trating a portion of the radiant heating section shown in Figure 3.

Figure 6 is a flow diagram in perspective illustrating a portion of the radiant heating section shown in Figure 4.

Referring to Figure 1, 10 indicates a furnace or refractory setting which may conveniently be of box or rectangular shape. The furnace is provided with bridge walls 11 and 12, which separate the furnace into combustion or fire chambers 13 and 14 and a convection heating section 15. Burners are indicated at 16 and 17, in the fire chamber 13, and at 18 in the fire chamber 14. A screen or baffle wall 19, which may be perforated, is placed intermediate the burners 16 and 17.

One stream of oil to be heated may be admitted through an inlet 20 to a coil or tubular section 21 located in the cooler section of the 20 convection heating zone 15. The oil passes from the convection coil 21 to a coil comprising wall tubes 22 disposed about the walls of the fire chamber 14. The coil 22 may well be disposed about the four walls of the chamber consisting 25 of one side of the bridge walls 11 and 12 and the side walls of the furnace. The heated oil passes from the coil 22 through a coil of roof tubes 23 adapted to receive radiant heat from the fire chamber 14, the oil being then discharged through 30 outlet 24.

The other stream of oil is shown as being introduced to an inlet 25 to a convection heating coil 26 positioned in the hotter portion of the convection heating zone 15. The oil passes thence 35 through an intermediate radiant tube section 27 disposed about the baffle 19. The oil is then directed through a row of wall tubes 28 disposed in the chamber 13 along the other side of the bridge wall 11 and passes thence through floor tubes 29 to wall tubes 30 disposed adjacent one 40 of the walls 10 of the furnace. The oil then passes through a radiant heating coil 31 disposed about the four walls of the fire chamber 13 comprising the bridge wall 11 and three walls of the furnace 10. At the upper end of the bridge wall 11 the four-wall tube section is changed to a three-wall section 32, through which the oil 45 passes to radiant roof tubes 33 and out through the outlet 34.

It is preferable to provide in addition to the burners 16, 17 and 18 corresponding burners entering from the opposite wall to that from which the burners 16, 17 and 18 enter. It is to be understood, however, that any number of burners 50 may be employed without departing from the scope of the invention. It is contemplated that the flames of the burners are projected inwardly and that the combustion gases rise in combustion chamber 13 to flow over the bridge wall 11 to be there contacted with the combustion gases rising

in the combustion chamber 14, the combined gases then passing into the convection section to flow over the tubes in that section and finally passing to a flue or chimney (not shown). Thus, all of the tubes disposed along the several surfaces, that is, the various wall tubes, floor tubes, roof tubes and the tubes adjacent the intermediate screen or baffle 19 are heated substantially by radiant heat while the tubes located in the chamber 15 are heated by convection heat.

The heating apparatus of Figure 1 may be employed for various purposes, such for example, in the cracking of hydrocarbon oils, in which case both of the separate streams may be subjected to cracking temperatures, or if desired only one of the streams may be brought to a cracking temperature while the other stream may be more moderately heated. In one exemplification of the invention contemplated, one of the streams is employed as a high temperature cracking stream wherein considerable cracking may take place for the production of gasoline while the other stream may be subjected to a more moderate temperature, such for example, as may be applied to a crude petroleum or residuum thereof for the purpose of enabling a moderate degree of cracking for the breaking or reducing of the viscosity of the oil. The discharge pipes 34 and 24 may be connected to suitable distilling apparatus or to such reaction chambers as may be desired.

In the apparatus shown in Figure 2, a furnace 10a is provided with bridge walls 11a and 12a to form fire chambers 13a and 14a and a convection chamber 15a. The fire chamber 13a is supplied with burners at 16a and 17a, while the fire chamber 14a is supplied with burners 18a. In one or more of the combustion chambers, such as is shown in the combustion chamber 13a, baffles or screens 19a, similar to the baffle 19, are disposed intermediate the several burners. The baffles or screens may conveniently be supported on pedestals 35.

The apparatus of Figure 2 is shown as applied to the heating of two separate streams of oil, one of which is heated entirely by radiant heat and the other of which is heated partly by radiant heat and partly by convection heat. Thus, one stream may be introduced through an inlet 36 to a row of wall tubes 37 adjacent the bridge wall 11a, thence to a section of floor tubes 38, thence to intermediate radiant tubes 39 disposed about the surfaces of one of the screens 19a, thence to another section of floor tubes 40, thence to another section of intermediate radiant tubes 41 disposed about the other screen 19a, thence to floor tubes 42 and thence to a row of side wall tubes 43 along one of the walls 10a. The oil then passes through a section of four-wall tubes 44 disposed about the four walls of the combustion chamber 13a, including the bridge wall 11a. At the upper end of the bridge wall the four-wall tubes are changed to a three-wall section 45, from which the oil passes finally through roof tubes 46 to an outlet 47. Each section, other than the roof, of the several sections of coil just mentioned is shown as provided for dual flow, that is, each section consists of pairs of pipes inter-connected so that the oil flows in two parallel streams through the several pairs of tubes of which each section is composed. If desired, however, the arrangement may be such that there is single flow entirely through all of the several coils. The stream thus introduced at the inlet

36 may be substantially entirely heated by radiant heat.

The other stream of oil enters through an inlet 48 through a coil section 49 positioned in a cooler section of the convection zone 15a, passes thence to a coil section 50 positioned in the hottest portion of the convection section 15a. The coil section 50 may advantageously, although not necessarily, consist of only a comparatively small section of coil, such as the two rows indicated, and may form a screening section through which relatively low temperature oil may be passed to thus protect the subsequent rows immediately underneath through which oil at a higher temperature may pass. The oil passes from the coil 50 to wall tubes 51 disposed adjacent the bridge wall 12a, thence through floor tubes 52, thence through a row of wall tubes 53 adjacent the bridge wall 11a, thence through a four-wall section of tubes 54 which are disposed about the walls of the combustion chamber 14a, including the bridge walls 11a and 12a and the side walls of the furnace. The oil then passes through a section of roof tubes 55 and finally through a coil section 56 disposed in an intermediate portion of the convection zone 15a and is finally discharged through an outlet 57. The flow of oil of this second stream is also shown to be dual.

While the apparatus of Figure 2 may be employed for various purposes one advantageous application of this apparatus is in the carrying on of a combined crude reducing or a viscosity breaking operation with a cracking operation for the production of cracked gasoline. Thus, for example, a heavy crude or reduced crude, which it is desired to skim or strip or to crack to a comparatively slight extent, such as in a mere viscosity breaking operation, may be introduced through the inlet 48 and passed through the several sections of the coil positioned in the radiant heating zones of the fire chamber 14a and in the convection zone 15a, the oil being then discharged through outlet 57 for distillation, while a cycle condensate obtained in the process may be passed to the inlet 36 and passed through the several sections of radiant heat coils disposed about the several walls of the fire chamber 13a wherein the oil is cracked to the desired degree and may then be discharged through the pipe 41 into a reaction chamber for further cracking or passed directly to suitable distilling apparatus.

In Figures 3 and 4, a furnace or refractory setting 10c is provided with bridge walls 11c and 12c to form combustion chambers 13c and 14c and a convection heating section 15c. The fire chamber 13c is supplied with burners at 16c and 17c and the fire chamber 14c is supplied with burners at 18c. Intermediate the several burners 16c and 17c in the fire chamber 13c are baffles or screens 19c, which may be suitably supported on pedestals 35c. Intermediate the several burners 18c in the fire chamber 14c are baffles or screens 22, which may be suitably supported on pedestals 73.

The stream of oil to be treated in the apparatus of Figures 3 and 4 enters through an inlet line 74 to a section of coil 75 positioned in the convection heating zone 15c. The flow of oil through the coil 75 is indicated as being in quadruplet. The oil passes from the coil 75 through a connecting line 75' having branches 76, 77, 78 and 79. The oil in branch line 76 passes to a side wall section of tubes 80 in the combustion chamber 14c adjacent the bridge wall 12c, thence

through floor tubes 81, thence through tubes 82 disposed along the surfaces of one of the baffles 12, thence through an additional section of floor tubes 83 to a transfer line 84. The stream of oil entering the branch line 77 passes through wall tubes 85 in the fire chamber 14c adjacent one side of the bridge wall 11c, thence through floor tubes 86, thence through a section coil 87 disposed about the other baffle 72, thence through floor tubes 88 to a transfer line 89. The oil entering the pipe 78 passes through wall tubes 90 disposed along the other side of the bridge wall 11c in the combustion chamber 13c, thence through floor tubes 91, thence through tubes 92 disposed along the surface of one of the intermediate screens 19c and thence through additional floor tubes 93 to a transfer line 94. The oil entering the other branch line 79 passes through wall tubes 95 adjacent one of the outer walls 10c, thence through floor tubes 96, thence through tubes 97 disposed along the surface of the other intermediate screen 19c, thence through floor tubes 98 to transfer line 99.

The streams in the transfer lines 84 and 89 are merged in a line 100 for delivery to a four-wall coil section 101 disposed about the walls in the fire chamber 14c, including the bridge walls 11c and 12c and the side walls of the furnace, the oil flowing in dual flow through the coil 101. The oil then passes in dual flow through a three-wall section 102 along the surfaces of the combustion chamber 14c, including the bridge wall 11c and the side walls of the furnace. The oil then passes to a two-wall section 103, one of the dual streams of oil from the coil 102 passing through one of the side wall coils 103 and the other stream passing through the other side wall coil 103, these side wall coils being located on opposite furnace walls in the fire chamber 14c. The oil finally passes to roof tubes 104 in dual flow and thence to an outlet pipe 105.

The streams of oil in the lines 94 and 99 are merged in the line 106 by which they are conducted to a four-wall coil 107 disposed about the walls of the fire chamber 13c, including three walls of the furnace and the bridge wall 11c. The oil passes thence through a three-wall section of coil 108 disposed about the three walls of the furnace. Finally the oil passes through roof tubes 109 to outlet 110. The flow of oil through each of the coils 107, 108 and 109 is shown in dual flow.

The apparatus illustrated in Figures 3 to 6 is particularly adapted for the cracking of hydro-carbon oils, and it is contemplated that the oil at cracking temperature may be delivered through the transfer lines 105 and 110 to a suitable reaction vessel or to a suitable distilling apparatus or both.

The baffles or screens positioned in the fire chambers for supporting additional heating coils, may be perforated if desired. By perforating the baffles or screens, it is possible for the hot gases of combustion to pass through the sections of coil positioned adjacent the surfaces of the baffles or screens. By this expedient, additional heating of the oil passing through these sections of coil may be accomplished.

An important feature of the invention is the provision of unitary heating apparatus of maximum capacity. This feature is particularly exemplified in the apparatus of Figures 3 to 6 in which a furnace structure is provided of considerably greater capacity than has hitherto been possible.

It is contemplated that in the apparatus shown, additional burners may be provided as on the opposite walls from those in which the burners are placed. In the several structures shown in these several figures the various radiant heating tubes located adjacent the interior surfaces of the fire chambers are preferably placed substantially out of the path of the convection gases so that they may not be subjected to direct convection heat in the fire chambers and are heated by the radiant heat afforded by the several burners in the fire chambers. It is contemplated that the furnace gases after being passed from the fire chambers to one of the convection zones and after flowing over the elements to be heated therein may be passed to a suitable flue or chimney, not shown. In one method of operation contemplated by the invention, the convection heating section may be eliminated and the furnace gases which are discharged from the fire chambers may be employed in preheating the air supply to the burners.

The separate control of the degree of radiant heat applied in the several radiant heating zones provided by the invention is an advantageous feature thereof, particularly in the case of cracking operations. Thus, the oil stream passing through the furnace may be rapidly raised to a cracking temperature and the soaking heat required in the final sections of the coil may be very accurately controlled in accordance with my invention.

An important method of operation contemplated by the invention is to heat separate streams of oil which may have different characteristics requiring different degrees of heat for cracking in separately controlled radiant heating sections. Thus for example, in the apparatus of Figure 1, one stream of oil after preferably being preheated in the convection coil 26 may be passed through the radiant conduits positioned in the fire chamber 13 while another stream of oil after being preferably preheated in the convection coil 21 may be passed through the radiant heating conduits of the fire chamber 14, the fire chambers 13 and 14 being separately controlled so that the desired cracking temperature may be applied in each instance. The two separate streams of oil may be derived from various sources, thus, one stream may be raw charging stock while the other may be cycle condensate obtained in the process or both streams may be withdrawn from the fractionating zone of the system but removed from different points therein. In the apparatus of Figures 3 and 4, for example, two cuts may be withdrawn from the fractionating zone, one cut being passed through the radiant heating conduits of the fire chamber 13c while the other stream may be passed through the radiant heating conduits of the fire chamber 14c or if desired a greater number of cuts of varying boiling points may be withdrawn from the fractionating zone and passed through separately controlled radiant heating zones of the furnace.

It is to be understood that this invention comprehends that the tubes may function to shield a part or all of the interior surfaces of the furnace adjacent which they are positioned to such an extent that they will radiate little or no heat, although if desired, the arrangement may be such that the walls may function as heat radiating or reflecting surfaces.

While there is shown and described the pre-

ferred embodiments of the invention and specific examples of operation for each, it is to be clearly understood that the invention is not to be limited by the precise details of construction herein set forth, by way of illustration, as it is apparent that many changes and variations may be made therein, by those skilled in the art, without departing from the spirit of the invention, or exceeding the scope of the appended claims.

This case is filed as a division on my application Serial No. 598,792, filed March 14, 1932, for Heating apparatus.

I claim:

1. A heating apparatus of the character described comprising a furnace provided with a plurality of bridge walls arranged to form a plurality of fire chambers and a convection chamber disposed to receive furnace gases flowing over the bridge walls from the fire chambers, a plurality of burners in each of said fire chambers, a screen disposed between burners in at least one of said fire chambers and heat absorbing elements disposed along the surfaces of said screen and along the walls of the fire chambers.

2. In a furnace having walls forming a combustion and radiant heating zone, the combination of fluid heating means, comprising a vertical row of horizontal tubes, centrally disposed in said zone, a horizontal row of serially connected, horizontal tubes in the lower portion of said zone beneath said fluid heating means, a second horizontal row of serially connected, horizontal tubes in the upper portion of said zone above said fluid heating means, and means for supplying fuel to said zone on opposite sides of said fluid heating means.

3. In a furnace having a pair of spaced vertical walls, a roof and a floor, the combination of a vertical row of horizontal tubes between and spaced from said walls, a horizontal row of serially connected, horizontal tubes adjacent the roof above said vertical row of tubes, a horizontal row of serially connected, horizontal tubes adjacent the floor beneath said vertical row of tubes, and means for burning fuel in the space between said vertical row and each of said walls.

4. A furnace comprising walls forming a pair of combustion zones and a convection heating zone, heating tubes in the convection zone and means for passing combustion gases from both said combustion zones through the convection zone, a vertical row of horizontal heating tubes in each of the combustion zones, means for firing each of the combustion zones on opposite sides of the vertical row of tubes therein, a horizontal row of heating tubes in the lower portion of each of the combustion zones below the vertical row of tubes therein, and a horizontal row of tubes in the upper portion of the furnace and having tubes disposed in each of the combustion zones.

5. In a furnace for heating hydrocarbon oils comprising a main furnace structure having side walls, end walls, a roof and a floor, the combination with vertical partition walls between said sides of the main furnace structure dividing the same into a plurality of separate combustion and heating zones, means for independently supplying combustibles to each combustion zone, means for removing combustion gases from each combustion zone and passing the same through a convection heating zone, a fluid conduit located within said convection heating zone and supplied with available convection heat from said combustion gases, a communicating fluid conduit located adjacent the floor of the furnace

directly beneath said combustion zones and comprising horizontally disposed tubes heated by direct radiation from the combustion gases, another communicating fluid conduit between and spaced from said side walls comprising a vertical row of horizontal tubes in each combustion and heating zone, and means for subjecting said fluid conduit in said heating and combustion zones to direct radiation from flames.

6. In a furnace for heating hydrocarbon oils comprising a main furnace structure having side walls, end walls, a roof and a floor, the combination with vertical partition walls between said sides of the main furnace structure dividing the same into a plurality of separate combustion and heating zones, means for independently supplying combustibles to each combustion zone, means for removing combustion gases from each combustion zone and passing the same through a convection heating zone, a fluid conduit located within said convection heating zone and supplied with available convection heat from said combustion gases, a communicating fluid conduit located adjacent the floor of the furnace directly beneath said combustion zones and comprising horizontally disposed tubes heated by direct radiation from the combustion gases, another communicating fluid conduit between and spaced from said side walls comprising a pair of parallel vertical rows of horizontal tubes in each combustion and heating zone, and means for subjecting said fluid conduit in said heating and combustion zones to direct radiation from flames.

7. A furnace comprising walls forming a pair of combustion zones and a convection heating zone, heating tubes in the convection zone and means for passing combustion gases from both said combustion zones through the convection zone, a vertical row of horizontal heating tubes in each of the combustion zones, means for firing each of the combustion zones on opposite sides of the vertical row of tubes therein, and a horizontal row of heating tubes in the lower portion of each of the combustion zones below the vertical row of tubes therein.

8. In a furnace having a combustion zone and a convection zone adapted to receive combustion gases from the combustion zone, the combination of a plurality of banks of heating tubes so arranged in the convection zone as to be substantially uniformly heated by said gases, a row of serially connected floor tubes and a row of serially connected roof tubes in the combustion zone, means for passing fluid to be heated in a plurality of parallel streams through the banks of tubes in the convection zone, and means for passing a portion of the fluid heated in said convection zone through said floor tubes and for passing another portion of the fluid heated in said convection zone through said roof tubes.

9. In a furnace having at least two combustion zones and a convection zone adapted to receive combustion gases therefrom, the combination of a plurality of banks of heating tubes so arranged in the convection zone as to be substantially uniformly heated by said gases, a row of serially connected floor tubes in one of said combustion zones and a row of serially connected roof tubes in another of said combustion zones, means for passing fluid to be heated in a plurality of parallel streams through the banks of tubes in the convection zone, and means for passing a portion of the fluid heated in said convection zone through said floor tubes and for

passing another portion of the fluid heated in said convection zone through said roof tubes.

10. A furnace for the heating of fluids which comprises, in combination, two separate combustion and heating zones, means for independently supplying hot combustion products in regulated amounts to each combustion and heating zone, a convection heating zone forming part of said furnace and associated with said separate combustion and heating zones, means for passing combustion gases from each combustion and heating zone through said convection heating zone, a fluid conduit located adjacent the roof of each combustion and heating zone, a fluid conduit located adjacent the floor of each combustion and heating zone, a fluid conduit located within the convection heating zone, means for passing hydrocarbon oil in a continuous stream through the fluid conduit adjacent the floor of one combustion and heating zone and then through the fluid conduit adjacent the roof of the same zone, means for simultaneously passing a different hydrocarbon oil in a continuous stream through the fluid conduit in the convection heating zone, then through the fluid conduit adjacent the floor of the other combustion and heating zone and then through the fluid conduit adjacent the roof of the last mentioned combustion and heating zone.

11. In the heating of hydrocarbon fluids to conversion temperature in furnaces of the character having a pair of independently fired combustion zones and a convection zone supplied with combustion gases from both of said combustion zones, the method which comprises passing a hydrocarbon oil in a continuous uninterrupted stream through one of said combustion zones adjacent the floor and adjacent the roof thereof, simultaneously passing a second hydrocarbon oil in a continuous uninterrupted stream through the convection zone and through the other of said combustion zones adjacent the floor and adjacent the roof thereof, the streams being subjected to strong heating while adjacent the floor of each combustion zone.

12. A method of heating hydrocarbon fluids to conversion temperature in a furnace having a bridge wall and a combustion chamber which comprises passing hydrocarbon fluid through spaced vertical banks of tubes arranged in said combustion chamber to subdivide it into a plurality of heating sections, separately supplying hot products of combustion to each heating section to direct products of combustion between said banks of tubes in each heating section, subjecting the tubes to heat radiated directly from hot products of combustion supplied to each heating section to thereby apply radiant heat to exposed sides of each of said tubes in intermediate banks of tubes, passing at least part of the hydrocarbon fluid first through a bank of tubes adjacent the wall opposite said bridge wall and thence through an intermediate bank of tubes and commingling the hot products of combustion leaving said heating sections and withdrawing the commingled hot products of combustion through a common outlet adjacent said bridge wall.

13. In a furnace for heating hydrocarbon oils comprising a main furnace structure having side walls, end walls, a roof and a floor, the combination with partition walls extending between said sides from near the floor towards the roof

of the main furnace structure dividing the same into a plurality of separate combustion and heating zones, means for independently supplying combustibles to each combustion zone, means for

5 removing combustion gases from each combustion zone and passing the same through a convection heating zone, a fluid conduit located within said convection heating zone and supplied with available convection heat from said 10 combustion gases, a communicating fluid conduit located adjacent the floor of the furnace directly beneath said combustion zones and comprising horizontally disposed tubes heated by direct radiation from the combustion gases, another 15 communicating fluid conduit between and spaced from said side walls comprising a pair of parallel vertical rows of horizontal tubes in each combustion and heating zone, and means for subjecting said fluid conduit in said heating and 20 combustion zones to direct radiation from flames.

14. In a furnace for heating hydrocarbon oils comprising a main furnace structure having side walls, end walls, a roof and a floor, the combination with vertical partition walls between

25 said sides of the main furnace structure dividing the same into a plurality of separate combustion and heating zones, means for independently supplying combustibles to each combustion zone, means for removing combustion

30 gases from each combustion zone and passing the same through a convection heating zone, a fluid conduit located within said convection heating zone and supplied with available convection heat from said combustion gases, a com-

35 municating fluid conduit located adjacent the floor of the furnace directly beneath said combustion zones and comprising horizontally disposed tubes heated on one side by direct radiation from the combustion gases and on the

40 opposite side by reflected radiation from the floor, another communicating fluid conduit comprising a vertical row of horizontal tubes in each combustion and heating zone and means for subjecting opposite sides of said last-mentioned fluid

45 conduit in said heating and combustion zones to direct radiation from flames.

15. In a furnace for heating hydrocarbon oils comprising a main furnace structure having side walls, end walls, a roof and a floor, the combination with vertical partition walls between said

50 sides of the main furnace structure dividing the same into a plurality of separate combustion and heating zones, means for independently supplying combustibles to each combustion zone, means for removing combustion gases from each

55 combustion zone and passing the same through a convection heating zone, a fluid conduit located within said convection heating zone and supplied with available convection heat from

60 said combustion gases, a communicating fluid conduit located adjacent the floor of the furnace directly beneath said combustion zones and comprising horizontally disposed tubes heated on one side by direct radiation from the combustion

65 gases and on the opposite side by reflected radiation from the floor, another communicating fluid conduit comprising a pair of parallel vertical rows of horizontal tubes in each combustion and heating zone, and means for subjecting said last-mentioned fluid conduit in said heating and combustion zones to direct radiation from flames.

DUSTIN W. WILSON.
